John P. Nikonow
INVENTOR

UNITED STATES PATENT OFFICE.

JOHN P. NIKONOW, OF NEW YORK, N. Y.

FOUNTAIN PEN.

Application filed March 22, 1928. Serial No. 263,916.

My invention relates to fountain pens and has a particular reference to covering attachments or caps for fountain pens.

Ordinary fountain pens are usually provided with removable caps which are fitted on the body of the pen on the operating end of it. In order to remove or to replace such cap it must be taken in one hand and the body in the other, so that two hands are required for such operation.

In my fountain pen I provide a cap which is slidably fitted on the body of the pen. It provides an enclosure for the operating end when moved to its extreme outer position, and exposes the pen point if it is moved back. This movement can be accomplished by a single hand, holding the body in the palm of the hand and sliding the cap between the thumb and forefinger. This arrangement permits much easier and quicker handling of the pen than with the removable cap.

My invention is more fully described in the accompanying specification and drawing in which—

Fig. 1 is a sectional elevation of my pen with the cap in a closed position, Fig. 2 is a similar view with the cap open, Fig. 3 is an end view of a cap in a closed position, Fig. 4 is the same for an open position, Fig. 5 is a side view of the cover plate, and Fig. 6 is a view of a modified cover plate.

My fountain pen consists of a body 1 with a pen point 2 on its operating end. The body is tapered off toward the operating end and is provided with a shoulder 3. A tubular cap 4 is slidably fitted on the cylindrical portion of the body 1 and is provided with a spring clip 5 inside which rests against the shoulder 3 when the cap is moved to its extreme closing position, thereby preventing the cap from sliding off the body and retaining it in its proper closing position. A notch 6 is made in the body 1 for the clip 5 retaining the cap in its open position when moved to the rear as shown in Fig. 2. This notch is very small and does not prevent the cap from being moved if sufficient pressure is applied, serving only to keep the cap from sliding on its own accord.

The tube 4 is recessed inside to make room for the spring clip 5 in an open position as shown in Fig. 2. An outside clip 7 is attached to the cap for holding same on the edge of a coat pocket.

A recess 8 is provided in the upper or outer portion of the cap 4 for a spring 9 which is riveted to the wall of the cap on one

end and with the other end presses against the cam-shaped end 13 of a cover 10. The shape of the cam is such that the spring 9 tends to keep the cover 10 down, pressed against a shoulder 11 inside of the cap 4. The tail end of the cover 10 is rotatively mounted on a pin 12. The cover 10 is bent on an arc of a circle of the same radius as the inside diameter of the tube 4, so that when the cap 4 is pushed back, the cover 10, being pushed against the pen point 2, swings out and lays against the inside wall of the tube 4 as shown in Fig. 2 and viewed from the end in Fig. 4. The shoulder 11 is curved to conform to the curvature of the cover 10. The cover rests at an angle as shown in Fig. 1 in order to reduce the angle of its movement. In order to reduce its curvature it may be made of a flexible material, such as rubber or celluloid, as shown in Fig. 6. In this case it will be forced against the wall by the pressure of the body 1 in an open position corresponding to Fig. 1.

In a closed position spring 9 keeps the cover 10 tightly against the shoulder 11 thereby fully enclosing the operating end of the pen. The spring 5 keeps the cap in a closed position resting against the shoulder 3. In this condition the pen may be carried in a coat pocket fastened to the pocket edge with the clip 7.

When it is desired to use the pen it is removed from the pocket and opened with the same hand. For this purpose the rear end of the pen body is held in the palm of the hand with two or three fingers and the cap is gripped with the thumb and forefinger and moved into open position until the clip 5 engages the recess 6. The pen may be then used with the same hand and it is not necessary to assist with the other hand. In the same manner the pen may be closed and replaced in the pocket with one hand.

This arrangement represents an important advantage of my pen as the other hand may be used for holding notebook, paper etc., and the pen may be quickly removed from the pocket, used and replaced, these operations taking much less time than with ordinary pens.

My cap may be also used with ordinary standard fountain pens. The recess 6 may be easily made in the body of a pen. My cap will also operate without such a recess as there is sufficient friction due to the pressure of the spring on the cover 10 to keep the cap in any position on the body 1 of the pen, especially

if the cover 10 is made flexible as shown in Fig. 6.

I claim as my invention:

1. In a fountain pen, the combination with a tubular cap open on both ends and slidably fitted over the body of a fountain pen, said cap being provided with a longitudinal recess inside, a flat spring attached with one end to said cap inside of said recess, the other end of said spring being bent so as to resiliently press against the body of said fountain pen and to bear against the circular shoulder on the operating end of said fountain pen near its pen point, when said cap is moved into inoperating position for said fountain pen, covering said pen point.

2. In a fountain pen, the combination with

a tubular cap open on both ends and slidably fitted over the body of a fountain pen, an outwardly extending pocket formed in the wall of said cap near its outer end, a cover in said tubular cap near its outer end, a lug on said cover pivotally supported in said pocket, and a spring in said pocket adapted to press against said cover tending to keep it in a closed position, said cover being adapted to be opened by the pressure from the pen point of said fountain pen when said cap is moved toward the rear end of said fountain pen.

Signed at New York in the county of New York and State of New York this 19th day of March, A. D. 1928.

JOHN P. NIKONOW.
